UNITED STATES PATENT OFFICE.

JESSIE KIDD, OF PITTSBURG, PENNSYLVANIA.

SMOOTHING-IRON.

SPECIFICATION forming part of Letters Patent No. 761,500, dated May 31, 1904.

Application filed September 16, 1903. Serial No. 173,438. (No model.)

To all whom it may concern:

Be it known that I, JESSIE KIDD, a citizen of the United States of America, residing at Pittsburgh, in the county of Allegheny and State of Pennsylvania, have invented certain new and useful Improvements in Smoothing-Irons, of which the following is a specification.

This invention relates to certain new and useful improvements in smoothing-irons, and more particularly to that class used in the pressing of shirt-waists, fine laces, silk embroidery, and the like.

Reference is to be had to the accompanying drawings, forming a part of this specification, in which similar characters of reference indicate corresponding parts in all the drawings.

Figure 1 is a perspective view of my improved smoothing-iron. Fig. 2 is a side view thereof, partly in section. Fig. 3 shows the position of iron when being heated.

The base 4 of the smoothing-iron support I make oblong in form, so there will be no possible danger of it tilting over when pressure is exerted on the iron A. Secured to the base by screws 5 or other fastening means is a socket 6, which is provided with an angular opening 7 for the admission of the end of the curved arm 8, the lower end of which is square to correspond with the socket-aperture, and the upper end of said arm extends approximately horizontally in the direction of the length of the base and is round in cross-section.

The smoothing-iron is provided with a round 35 socket in its edge to receive the end of the arm and is held rigid on the arm by the use of a set-screw 9. This will permit the iron to be tilted from side to side, as shown in dotted lines of Fig. 2, and permit each operator to adjust 40 the arm to suit his particular fancy.

In heating the iron upon the top of the stove arm 8, being near the surface of stove becomes hot. This is very objectionable in handling, as the iron must be removed from the 45 stove and mounted on the base. To overcome the danger of being burned, I wrap the arm with some fireproofing material 10, such as asbestos.

With the above and other objects in view 50 what I claim, and desire to secure by Letters Patent, is—

In a device of the character described, a base and socket, a curved arm secured in the socket, having its upper end extending approximately horizontally of the base and being round in cross-section, an iron having a round socket in its edge to receive the end of the arm whereby the iron is capable of rotation on the arm and means for securing the 60 iron on the arm at different adjustments.

In testimony whereof I affix my signature, in the presence of two witnesses, this 3d day of September, 1903.

JESSIE KIDD.
